UNITED STATES PATENT OFFICE.

ANTHONY M. ZOTTOLI, OF QUINCY, MASSACHUSETTS.

METHOD OF AND APPARATUS FOR MAKING BUILDING-BLOCKS.

1,374,270.

Specification of Letters Patent. Patented Apr. 12, 1921.

Application filed March 15, 1919. Serial No. 282,857.

To all whom it may concern:

Be it known that I, ANTHONY M. ZOTTOLI, a citizen of the United States, residing at Quincy, county of Norfolk, State of Massachusetts, have invented a certain new and useful Improvement in Methods of and Apparatus for Making Building-Blocks, of which the following is a specification, reference being had therein to the accompanying drawings.

The invention relates to a new and useful improvement in method of making flanged blocks of cementitious or other moldable material and apparatus therefor. The blocks especially intended to be made by my improved method and apparatus are blocks used in building construction having flanges so that when the blocks are assembled in the erection of the building, they may be disposed in such manner as to form hollow spaces in the walls. The invention is not limited however to use in the manufacture of blocks for the particular use above mentioned.

In the manufacture of such blocks heretofore it has been customary to make the blocks singly by the use of a mold former having on the under side a fin and then piling up the molding sand around against the outside walls of the former and underneath the same and tamping it down, then withdrawing the former so as to leave a recess in the sand, shaped to the contour of the block to be formed and having a groove in the bottom of the recess produced by the fin to correspond with the shape of the flange which is to be formed on the block. Sometimes it has been attempted to press the fin into the sand the depth of the fin so that it will then be necessary only to bank up the sand around the outside walls of the former and tamp it down and then remove the form. After the sand mold is thus formed the cementitious material is poured in and allowed to set, then the sand is drawn away from around the block so that the block can be removed. When it is constructed in this manner the sand mold is destroyed each time a block is made, and even if the block could be lifted out of the sand mold without entirely destroying the sand mold, still it has to be to some extent smoothed again before it can be used for another block and at the best only one block at a time can be made.

Moreover it is a slow and tedious process to 55 form the sand mold in this way. The object of the present invention is to provide a simple means whereby a plurality of blocks in series may be made simultaneously.

The invention will be fully understood 60 from the following description when taken in connection with the accompanying drawings and the novel features thereof will be pointed out and clearly defined in the claims at the close of this specification. 65

In the drawings, Figure 1 is a perspective view showing one form of grooving apparatus for forming the grooves in a bed of sand or other suitable mold material.

Fig. 2 is a side elevation of the apparatus shown in Fig. 1. 70

Fig. 3 is a plan view of the apparatus shown in Fig. 1.

Fig. 4 is a front end view of the apparatus shown in Fig. 3. 75

Fig. 5 is a perspective view of one form of block such as the apparatus is intended to make.

Fig. 6 is a perspective view of the mold frame which is to be employed in connection 80 with the grooved bed after the grooving apparatus has been removed.

Fig. 7 is a perspective view of the mold frame placed in position upon the grooved sand bed with the flange projections of the 85 partition members engaged in the grooves of the bed.

Fig. 8 is a perspective view of a modified form of mold for the flanges.

Fig. 9 is a perspective view of a modified 90 form of frame to coöperate with the groove member of Fig. 8 to form the partitions and top side portion of the mold.

Fig. 10 is a sectional view of the members shown in Figs. 8 and 9 assembled in coöperating relation.

Fig. 11 is a view showing a device to be employed in shutting off a part of the mold, so as to eliminate a portion of the block to adapt it to be used as a corner block. 100

Fig. 12 is a view showing the application of the cut off plate to the mold.

The apparatus is shown as constructed for making a mold for a two flange block and for convenience it will be so described. It 105 is understood, however, that the invention applies to apparatus for making a block having any number of flanges desired, the

particular number of flanges not being essential to the invention and the patent claims are not intended to be limited to apparatus or process of making blocks of any particular number of flanges.

Referring now to Figs. 1-7 of the drawings, 1 is the top frame which preferably is of skeleton formation having the side bars *a*, *a* and cross bars *b*, *b* suitably tied together to form a rigid frame. The particular form of construction of this frame is not essential and may be varied. Secured to the under side of this frame are the parallel grooving members 2, 2 which may be in the form of 10 runners or grooving boards. These are of a depth equal to the depth of the groove which is to be formed and of the same depth as the flanges which are to be formed on the blocks and spaced apart from each other equal to 15 the spacing between the flanges of the block. These runners may be of any convenient length desired. As shown in the drawings they extend some distance in front of the frame 1 and also in the rear of the 20 frame 1.

Secured to the inner faces of the runners 2, 2 at the forward ends thereof is a metal guard 3 preferably of inverted U-shape in cross section having the vertical 25 side members *c*, *c* and horizontal top *d*, the vertical sides *c*, *c* being secured to the inner faces of the runners and preferably extending also a short distance below the bottoms of the runners as shown in Fig. 4. Preferably also this guard 3 extends to some distance forward of the forward ends of the runners. The advance end portion of the guard 3 serves as a sort of plow to cut the way through the sand and prevents disturbance 30 of the portion of the sand or center core between the grooves. Preferably also the forward portion of each runner 2 which is faced on the inner side by the guard 3 extends down to some greater depth than 35 the portion in the rear of it as indicated by the off set 5 in Fig. 2. This variation in the depth of the runner is made because when a groove is formed by the forward portion of the runner the bottom of the 40 groove is left with loose sand which would leave a rough bottom to the groove and this is smoothed down and compressed by the rear portion of the runner.

As the apparatus is moved through the sand 45 the grooving runners will throw up more or less sand and it is desired to throw this to one side so as to level off the surface. For this purpose a spreader or deflector is provided on top of the apparatus at the front 50 which in the preferred form consists of a V-shaped element 6, the apex of the V being in the median line of the apparatus as shown in Figs. 1 and 3.

It is also desirable to compress the sand 55 on the surface on each side of the grooves

so as to form a flat top surface and to compact the sand. To this end there is provided a compressor member 7 which is pivotally connected to the apparatus in the rear of the body frame 1. This compressor has 70 a flat under face and is formed with slots 8, 8 the side walls of which straddle the runners as clearly shown in Fig. 1. The method shown of connecting the said compressor with the apparatus is by means of 75 screw eyes 9, 9 connected with the front end of the compressor which are linked with eyes 10, 10 connected with the tops of the runners. This, however, is merely one convenient form of making the connection and 80 any suitable flexible connecting means between the compressor and either the runners or the frame 1 may be employed. The rear end of the compressor is permitted to sag down below the level of the top of the 85 runners if necessary as shown in Fig. 2 so as to compress the sand in the rear. In order to give still greater compression it is preferable to provide a weight 11 mounted on top of the compressor as shown in Fig. 2. 90 This weight may be whatever experience shows is desirable. The compressor may if preferred be made sufficiently heavy in itself without employing additional weight, but I prefer a separable weight so that it can be 95 varied if desired.

Any suitable means may be provided for propelling or dragging the grooving device through the sand. As shown in the drawings there is shown a drafting rope 12 attached to a draft eye 13 at the forward end of the deflector 6 and this may be pulled by hand or by any other power convenient. It is important that the groover should be drawn through the sand by a horizontal pull. 100 In order that the grooving device may have a fair start the sand bed 14 should preferably be banked up as shown in Fig. 1 so that the groover may enter the rear end wall of the bed. 105

The sand bed should be of somewhat greater width than the length of the blocks to be formed and the length of the bed should be sufficient to equal that of a series of blocks of any number desired to be made 110 at one operation.

After the sand bed has been grooved a suitable frame is superimposed upon the bed having side walls and end walls which rise above the surface of the bed at least equal to 115 the thickness of the body of the block to be formed and which is provided with transverse partition plates which preferably are separable from the frame and which may be connected therewith at regular intervals 120 apart so as to form compartments each of which is of the size of one of the blocks to be formed. These partition plates are also provided with flange extensions which enter the grooves to form transverse partitions 125 130

therein. Suitable apparatus for this purpose is shown in Figs. 6 and 7 and is as follows:

The mold frame B has the two side walls 15, 15 and the two end walls 16, 16 the two side walls 15, 15 being spaced apart a sufficient distance so that the distance between them will be the length of one of the blocks. Transverse partition plates 17 are provided 10 each of which is provided with two downwardly extending flanges 18, 18 which are spaced apart from each other equal to the distance between the two grooves 19, 19 in the sand bed and the width of each flange 15 18 is equal to the width of one of the grooves. The frame B is placed in position 20 on the sand bed so that the flanges 18, 18 will enter the grooves 19, 19 in the sand bed as shown in Fig. 7 and the lower edge of the body of the partition 17 will rest upon the 25 top surface of the sand bed, thus forming a series of compartments between the partitions, each of which with its grooves will form a mold for the cement of which the block is to be formed.

The plastic cement will then be poured into the several compartments of the mold, filling the grooves and the spaces between the partitions above the grooves for the 30 requisite depth and the frame will then be allowed to remain in position until the cement partially sets. The frame will then be removed leaving the whole series of blocks on the sand bed and the blocks when fully 35 set can be removed from the sand.

Preferably the partitions 17 are removable from the frame, the said bars of the frame being slotted to permit the insertion and removal of the partition plates. The separable feature, however, is not essential to the 40 invention.

In the modified form of device shown in Figs. 8 to 12, instead of forming the grooves in a sand bed, a molding frame is formed of 45 any suitable material in such manner that the grooves for molding the flanges are formed in the frame itself. See Fig. 8 in which the grooved member of the frame has two outside parallel members C, D and an intermediate member E, said intermediate 50 member being spaced apart from the two side members C, D by the deep grooves 20, 20. These three members C, D and E are each formed with a flat top portion 21 and leg portions 22, the leg portions being spaced apart from each other as shown so as to form 55 a hollow interior, the hollow interior being for the sake of lightness of construction and for the saving of material and also for steam heating if desired. These frame portions 60 may be made of wood. The several members C, D and E may be tied together or assembled on a base and secured in their relative positions on the base. In the drawings 65 they are shown as fastened to the base or

floor 27 by angle plates 23 which are attached by screws. By leaving the grooves open at the ends two sets of frames may be set up end to end for the purpose of making a longer molding bed. In such case another 70 frame corresponding to that shown in Fig. 8 would be used, butting the end of one against the end of the other.

The frame members C, D and E are formed with transverse slots 24 cut in them 75 to receive the partitions of the coöperating member F as shown in Fig. 9. This coöperating or partition member is formed with two side bars 25, 25 and the transverse partition plates 26 spaced apart at the right 80 distance so as to form a series of compartments each equal in size to the size of the block to be formed. This partition member is assembled with the grooved member shown in Fig. 8 by placing one over the 85 other in such manner that the partition plates 26 will fit into the grooves 24. The partition members 26 are of such height in relation to the depth of the slots 24, that when the partition plates are seated in the 90 bottom of the slots the side bars 25 will project somewhat above the upper faces of the bed members C, D and E as will be seen by reference to Fig. 10. The side bars 25, 25 will straddle outside of the outer members 95 C, D of the grooved bed.

Preferably after the parts are assembled, sand 28 should be placed in the bottom of the grooves 20 to a sufficient depth so that the space from the top of the sand to the 100 faces 26 shall be equal to the length of the flanges to be formed on the blocks and the sand should be pressed down to make a hard smooth surface.

Preferably the side bars 25 are provided 105 with handles 29 so that the frame can readily be handled in assembling or separating it from the grooved member of the mold.

In order to permit a series of the frames to be assembled for an extension mold and 110 to be kept in proper alignment each side bar 25 is provided with a button 30 near one end which when turned in the position shown in Fig. 9 may lap over onto the contiguous side bar of a coöperating frame.

When the parts are assembled as shown in Fig. 10 it is obvious that the cementitious material of which the blocks are to be formed may be poured into the mold, filling the grooves 20 and spreading over the top 115 surfaces 21 for the requisite depth to form the thickness of the head of the blocks as previously described in connection with the Figs. 1-7.

The blocks used at the corners of the 120 building are of slightly different form as shown in Fig. 12 in which the head 30 of the block terminates at one end at the outer face of the flange 31. The same mold shown in Figs. 8, 9 and 10 can be employed in 125 130

making this form of block also by simply using in addition thereto an L-shaped plate 32 one arm of which extends down into one of the grooves 20 and the other arm of which lies over the top edge of one of the side bars 25 and one of the partition plates 26 so as to prevent the cementitious material from flowing into the portion of the mold which lies above the surface of one of the members C, D. The question as to which of the two members C or D should be covered will depend upon which side of the mold is to be blocked out. The leg portion of this shut off plate 32 will be formed with slots 33 to allow it to straddle the transverse partition plates 24.

What I claim is:

1. The method of forming flanged blocks of cementitious material consisting of moving a grooving member through a bed of mold material to form grooves of a length sufficient for a plurality of blocks, superposing upon the bed a frame having partition plates which divide the surface and grooves of the bed into compartments each of a size and shape to form a mold for one of the blocks, then pouring into the several compartments cementitious material in plastic state sufficient in amount for the blocks to be formed, then allowing the cementitious material to harden in the mold, then removing the frame.

2. The method of forming flanged blocks of cementitious material consisting of forming grooves in a bed of molding material of greater length than a single block to form a mold for the flanges of the block, superposing upon the surface of the bed a frame having walls and transverse partitions, said partitions having flange extensions which engage said grooves in the bed and form transverse partitions therein, said partitions dividing the frame and bed into compartments each of the size of one of the blocks to be formed, pouring into the several compartments cementitious material in a plastic state to fill the grooves and of a depth on the surface of the bed equal to the thickness of the head of the block, allowing the cementitious material to set until it hardens, then removing the frame.

3. The method of forming simultaneously a plurality of flanged blocks of cementitious material consisting of combining with a sand bed a frame in such manner as to form a mold with side and end walls and with longitudinal grooves in the bottom extending lengthwise of the mold and having transverse partitions which extend crosswise of the frame between the side walls, said partitions having flanges which extend down to the sand at the bottom of the groove and form partitions in the grooves, pouring into the mold cementitious material in a plastic state sufficient in quantity to

fill the grooves and spread over the surface in each compartment to a depth sufficient for the thickness of the head of the block, allowing the cementitious material to set, and then removing the frame.

4. The method of forming simultaneously a plurality of flanged blocks of cementitious material consisting of forming a combination mold of sand and frame work having a plurality of compartments with grooved bottom, pouring cementitious material in a plastic condition into all of said compartments, allowing the cementitious material to set while the frame is in position, then removing the frame.

5. The method of forming simultaneously a plurality of flanged blocks of cementitious material consisting of forming in a mold bed grooves corresponding with the flanges of the blocks to be formed continued in length sufficient for a plurality of blocks, then superposing upon the said bed a frame having end and side walls and transverse partition plates provided with flanges which enter the grooves in the bed and form transverse partitions in the grooves, then pouring cementitious material into the mold in sufficient quantity to fill the grooves and to give a depth on top of the bed above the grooves equal to the intended thickness of the body of the blocks to be formed, then allowing the cement to set and then withdrawing the frame and partitions.

6. The method of forming simultaneously a plurality of flanged blocks of cementitious material consisting of superposing a frame upon a bed which is formed with grooves corresponding in relative location and width to the flanges on the blocks to be formed, said grooves being continued in length sufficient for a plurality of blocks, said frame having end and side walls and transverse partition plates provided with flanged projections which enter the grooves in the bed and form transverse partitions therein, then pouring the cementitious material while in a plastic state into the mold formed by the grooves and frame in sufficient quantity to fill the grooves and to give a depth above the grooves equal to the intended thickness of the body of the blocks to be formed, then allowing the cement to set.

7. The method of forming simultaneously a plurality of flanged blocks of cementitious material consisting of forming a plurality of parallel grooves in a sand bed by moving through the bed a device having groove forming flanges and having means for smoothing and compressing the sand as the device is moved through it, then superposing upon the flattened top of the sand bed, a frame having end and side walls which rise above the flat top of the sand bed and which have transverse partitions formed with flanged extensions on the under side

- which project into said grooves and form transverse partitions therein, then pouring into the grooves and compartments formed by the partitions and the walls of the frame 5 cementitious material to fill the grooves and rise sufficiently above the tops of the grooves to a depth equal to the intended thickness of the body of the blocks and allowing the cementitious material to set.
- 10 8. The method of forming simultaneously a plurality of flanged blocks of cementitious material consisting of forming a plurality of parallel grooves in a sand bed by moving through the bed a device having groove forming flanges and having means for smoothing and compressing the sand as the device is moved through it, then superposing upon the flattened top of the sand bed a frame having end and side walls which rise above the 15 flat top of the sand bed and which have transverse partitions formed with flanged extensions on the under side which project into the said grooves and form transverse partitions therein, then pouring into the 20 grooves and compartments formed by the partitions and the walls of the frame cementitious material to fill the grooves and rise sufficiently above the tops of the grooves to a depth equal to the intended thickness of the body of the blocks and allowing the cementitious material to set, then separating the frame and partitions from the blocks.
- 25 9. The method of forming blocks of cementitious material consisting of forming a smooth surface on a bed of sand, superposing upon the sand bed a frame divided into a plurality of compartments each having a contour of one of the blocks to be formed and having a bottom open to the sand bed, pouring into the several compartments the cementitious material while in a plastic condition, allowing the frame to remain until the cementitious filling has become sufficiently set to retain its form, then 30 removing the frame.
- 35 10. A device for preparing a sand bed for use in molding blocks, said device having grooving members to be moved through the sand bed to form grooves in the sand of a depth equal to the flanges to be formed on the block, and having a drag which trails over the surface of the sand to smooth and compress the top surface of the sand by its 40 downward pressure.
- 45 11. A device for preparing a sand bed for use in molding flanged blocks consisting of a surfacing member to be moved over the surface of the sand to smooth and compress the sand, said surfacing member having connected therewith grooving members which as the surfacing member is moved form grooves in the sand of a depth equal to the flanges to be formed on the block, and a spreader member having portions which 50 diverge from each other in a rearward direc-

tion to spread the sand as it is thrown out by the grooving members.

12. A device for preparing a sand bed for use in molding blocks, said device having grooving members to be moved through the sand bed to form grooves in the sand of a depth equal to the flanges to be formed on the block, and having a drag which trails over the surface of the sand to smooth and compress the top surface of the sand by its 75 downward pressure, and a member with which motive power may be connected to move the said grooving members through the sand and to move the drag member over the surface of the sand.

13. A device for preparing a sand bed for use in molding blocks consisting of a drag having on the under side thereof a plurality of parallel grooving members and a spreader device mounted on the drag in the front part 85 thereof to deflect the sand which is thrown up at the forward end of the drag as it is moved through the sand.

14. A device for preparing a sand bed for use in molding blocks consisting of a drag 90 having on the under side thereof a plurality of parallel grooving members, a spreader device mounted on the drag in the front part thereof to deflect the sand which is thrown up at the forward end of the drag 95 as it is moved through the sand and a compressor loosely connected with the rear part of the drag having a compressor face which trails over the upper surface of the bed.

15. A device for preparing a sand bed for 100 use in molding building blocks consisting of a surfacing member to be moved over the surface of the sand, and a spreader device mounted at the front part of said surfacing member to deflect the sand which is thrown 105 up at the front end of the surfacing member.

16. A device for preparing a sand bed for use in molding flanged blocks consisting of a surfacing member to be moved over the surface of the sand to smooth and compress 110 the sand, said surfacing member having connected therewith a plurality of parallel grooving members which form grooves in the sand while the surfacing member moves over the surface, said grooving member having secured thereto thin plates which extend in advance of the grooving members to initially cleave the sand and protect the center sand core between the grooving members.

17. The method of forming blocks of cementitious material consisting of moving through a bed of mold material a member having a contour corresponding with the contour of the under surface of the block 115 to be formed, thereby shaping the surface of the bed to form a mold for the under side of the block, superposing upon the bed thus shaped a frame having partition members which divide the surface of the bed 120 125 130

into compartments each of the size and shape to form a mold for one of the blocks, then pouring into the several compartments cementitious material in plastic state sufficient 5 in amount for the blocks to be formed, then allowing the cementitious material to become set and then removing the frame.

18. The method of forming simultaneously a plurality of blocks of cementitious material consisting of combining with a sand bed a frame in such manner as to form a mold with side walls and with a sand bottom having a contour corresponding to the contour of the bottom of the block to be formed, 10 and having transverse partitions which extend crosswise of the frame between the side walls, and which extend down to the surface of the sand according to the contour of the bottom of the block to be formed, 15 pouring into the mold cementitious material sufficient in quantity to spread over the surface in each compartment to a depth sufficient for the thickness of the block, allowing the cementitious material to set and then 20 removing the frame.

19. The method of preparing a sand bed for use in molding blocks having flange projections thereon, consisting of moving through a sand bed a device having grooving 30 members to form grooves in the sand for the molding of the projections on the blocks, and moving a smoothing and compressing member over the top surface of the sand bed following the grooving action.

- 35 20. A method of casting concrete charac-

terized by presenting to an unconfined mass of sand a pattern device having a cavity forming portion and a sustaining portion, moving the device along the unconfined mass of sand to advance the cavity forming portion 40 through the sand to produce an elongated cavity, while the sustaining portion rests on the surface of the unconfined mass of sand adjacent the elongated cavity, placing partition members at intervals in the 45 elongated cavity to divide the same into a plurality of molds, and then pouring plastic concrete in the molds thus formed.

21. A method of casting concrete characterized by presenting to an unconfined mass 50 of sand a pattern device having a cavity forming portion and a sustaining portion, moving the device along the unconfined mass of sand any distance desired, while the sustaining portion rests on the surface of the 55 unconfined mass of sand and sustains the cavity forming portion at a uniform depth in the sand, and then pouring plastic concrete in the mold thus formed.

22. A method of making sand molds for 60 concrete, characterized by moving a pattern device along and through the sand to form a casting cavity of a length depending on the travel of said device, and then superposing on the sand a frame having partitions 65 for dividing the cavity into a plurality of molds to receive the concrete.

In testimony whereof I affix my signature.

ANTHONY M. ZOTTOLI.
